Des. 210,253
Patented Feb. 20, 1968

210,253

COMBINED PHOTOGRAPHIC LENS TURRET AND LIGHT SOURCE OR SIMILAR ARTICLE

Lester A. Dine, 145 Grist Mill Lane, Great Neck, N.Y.
11023, and Edward S. Lemmey, 56 Sterling Ave.,
Freeport, N.Y. 11520

Filed Mar. 29, 1966, Ser. No. 1,673

Term of patent 14 years

(Cl. D61—1)

FIG. 1

FIG. 2

FIG. 3

FIG. 4

FIG. 5

FIG. 6

FIGURE 1 is a front side perspective view of a combined photographic lens turret and light source or similar article showing my new design;

FIGURE 2 is a front elevational view;

FIGURE 3 is a side elevational view, the opposite side being substantially a mirror image thereof;

FIGURE 4 is a rear elevational view;

FIGURE 5 is a top plan view;

FIGURE 6 is a bottom plan view.

Portions of the drawing figures are diagonally lined to indicate transparency.

We claim:

The ornamental design for a combined photographic lens turret and light source or similar article, as shown and described.
